US0D1040648S

(12) **United States Design Patent** (10) **Patent No.:** **US D1,040,648 S**
(45) **Date of Patent:** **** Sep. 3, 2024**

(54) **CLAMP**

(71) Applicant: **RFD BEAUFORT LIMITED,**
Ellesmere Port (GB)

(72) Inventor: **Richard Griffin**, Prenton (GB)

(73) Assignee: **RFD BEAUFORT LIMITED,**
Ellesmere Port (GB)

(**) Term: **15 Years**

(21) Appl. No.: **29/866,708**

(22) Filed: **Sep. 23, 2022**

(30) **Foreign Application Priority Data**

Mar. 23, 2022 (GB) 6197715

(51) **LOC (14) Cl.** **08-08**

(52) **U.S. Cl.** **D8/394**

(58) **Field of Classification Search**

USPC D8/323, 327, 328, 337, 338, 343, 340,
D8/342, 382, 394; D12/233; D13/120;

D23/265; D26/60; D29/122, 130

CPC A44B 19/32; F16B 15/00; E05C 3/046

See application file for complete search history.

(57) **CLAIM**

The ornamental design for a clamp, as shown and described.

DESCRIPTION

FIG. 1 is a perspective view of an embodiment of a clamp; FIG. 2 a left side view of the clamp shown in FIG. 1; FIG. 3 is a right side view of the clamp shown in FIG. 1; FIG. 4 is rear view at the narrow end of the clamp shown in FIG. 1; and,

FIG. 5 is a front view at the wide end of the clamp shown in FIG. 1;

FIG. 6 is a top view of the clamp shown in FIG. 1; and,
FIG. 7 is a bottom view of the clamp shown in FIG. 1.

The broken lines in the figures represent portions of the clamp that form no part of the claimed design.

1 Claim, 7 Drawing Sheets
